ELECTRICAL EQUIPMENT HOUSING

Walter G. Hodsdon, Framingham, Mass., assignor to Space and Tactical Systems Corporation, Burlington, Mass., a corporation of Massachusetts

Filed June 3, 1968, Ser. No. 12,176

Term of patent 14 years

Int. Cl. D14—99

U.S. Cl. D26—1

The single figure is a front perspective view of an electrical equipment housing showing my new design.

The undisclosed end of the housing is similar to the end shown and the rear and bottom of the housing is similar to the top surface as shown.

The essential features of the design reside in the full line portions thereof.

I claim:

The ornamental design for an electrical equipment housing, as shown and described.
